PLASTIC BAG MACHINE

John Bonura, 616 Schenck Ave., Brooklyn, N.Y.
Filed Nov. 29, 1961, Ser. No. 155,605
6 Claims. (Cl. 242—56)

My invention is directed toward a machine which produces in rapid succession a plurality of tubes, each of which carries in the form of a roll a plurality of plastic bags in collapsed sheet form and joined end to end.

It is an object of my invention to provide a new and improved machine of the character indicated.

Another object is to provide a machine of the character indicated wherein the plurality of bags rolled on each tube is accurately and automatically set to a desired value.

Still another object is to provide a machine of the character indicated which includes a novel mechanism for wrapping a plurality of plastic bags in collapsed sheet form about a hollow tube.

Yet another object is to provide a machine of the character indicated wherein a predetermined number of plastic bags in collapsed sheet form are unrolled from a supply roll carrying these bags in the form of a rolled sheet and are thereafter rolled into a tube, the sheet being severed automatically at the proper time and at the proper position.

These and other objects of my invention will either be explained or will become apparent hereinafter.

An illustrative embodiment of my invention will now be described with reference to the accompanying drawings wherein:

FIGURE 1 is a front elevation of a bag machine in accordance with my invention.

FIGURE 2 is a partially cut-away side elevation of the machine of FIGURE 1.

FIGURES 3 and 5 illustrate schematically the bag tearing action required in the machine of FIGURE 1.

FIGURE 6 is a partial sectional view of the tube wrapping mechanism of the machine of FIGURE 1.

FIGURE 7 is a cross-sectional view taken along the line 7—7 in FIGURE 6.

FIGURES 8 and 9 are respectively plan and elevation views of a mechanism for cutting the material employed in the machine of FIGURE 1 after a sufficient length of material has been wrapped on a tube as fed into the machine of FIGURE 1. The mechanism of FIGURES 8 and 9 can be employed together with the tensioning movement of rolls 14a and 14b to sever the material at an appropriate location, or may be used independently of the tensioning rolls 14a and 14b to sever the material.

Referring now to the drawings, a supply roll 10 carries a long length of plastic bag material 11. This material consists of a plurality of equal lengths (units) of double sheets joined end to end. The double sheets are sealed together at the joints 18 and are also perforated for easy tearing along a line 19 which extends through each joint 18 in a direction parallel to the axis of roll 10. Guide roll 12 feeds material 11 downward from roll 10 down the center of the machine frame 13a and 13b, between tearing rolls 14a and 14b, then between stationary rolls 15a and 15b. Thereafter material 11 is wound or wrapped around tube 16. After a predetermined number of material units (each of which can constitute a separate bag) has passed by a selected position intermediate the tearing rolls 14a and 14b and the stationary rolls 15a and 15b, the last unit in this predetermined number is pulled away from the remaining material 11. At the same time a knife 83 severs the joint between the last unit and the remaining material. After the severed length of material has been wrapped around tube 16, this wrapped tube is

2

released from the machine and dropped into container 17.

Rolls 14a and 14b are geared together at 24 and rotate in opposite directions. Similarly rolls 15a and 15b are geared together at 25 and rotate in opposite directions.

5 (This arrangement is used to provide positive movement of material 11 along the lines of contact between the two sets of rolls.)

The machine is provided with conventional properly synchronized and timed speed drives (not shown) at 26, 10 27, 28, 29a, 29b and 30. The motion at 28 is transferred to gears 31 and 32 (to rotate the rolls 14a-14b and 15a-15b respectively).

15 At the instant the machine is started, electrical energy is fed through wires 22, metal rings 20a and 20b (which are in contact) and the commutating rings 21a and 21b (which are in respective connection with rings 20a and 20b) to solenoid 23 and energizes same. Plunger 40 of solenoid 23 then protrudes and will stop the rotation of friction disc 36 by arresting arm 37 attached to disc 36 when element 39 touches it. In this position element 39 is in position 41.

20 When material 11 is introduced downward between rolls 15a and 15b, the electrical circuit is broken and solenoid 23 is deenergized. Plunger 40 is withdrawn, and 25 the rotary motion of rolls 15a and 15b is transmitted through gears 33 and 34 to shaft 35. (The gearing is such that shaft 35 makes just under one revolution in the period in which the predetermined number of bags, for example 25 bags, is passed through the machine.) Shaft 35 then rotates and rotates arm 37. After the 25th bag has passed and therefore shaft 35 has almost completed one revolution, cam 38 lifts cam follower 42 causing clutch 43 to move into driver engagement with member 44. Since member 44 is continuously driven through bevel 30 gears 45 by drive 30, assembly 46a and sprocket 47 rotates. By means of chain 48 connected between sprockets 47 and 49, assembly 46b and sprocket 49 also rotate. As assemblies 46a and 46b rotate, cams 50a and 50b bear against links 51a and 51b. This action causes rolls 14a and 14b to move upwards relative to rolls 15a and 15b, thus producing a tearing force at the joint 18 at which the 25th unit or bag is joined to the remaining material 11 fed from supply roll 10. (See FIGS. 4 and 5.)

45 At the same time either in conjunction with the tensioning movement of rolls 14a and 14b, or independent thereof, as shown in FIGURES 8 and 9, a horizontal line through this joint 18 is cut therethrough by knife 83. Knife 83 is moved horizontally by a belt driven assembly 50 82 which is driven by motor 86. Since the position of 55 the cutting line is critical, motor 86 is energized by a photoelectric unit 84 when the appropriate joint 18 passes the desired position. (Alternatively, a register dot or line can be imprinted on each joint 18, and unit 84 can sense this dot or line). Unit 84 is set to count the passage of 60 24 bags or units before initiating the cutting operation on the 25th bag. It is to be noted that as indicated in FIGURE 9, the motion of knife 83 has a downward component parallel to the downward movement of the bag material. Consequently, for the angle that the belt is relative to the axis of the bag material, there is a predetermined speed for the belt in relation to the bag material speed, which will cause it to move downward at the same velocity as the bag material, whereupon the only relative motion during the cutting period, will be the transverse movement of the knife relative to the bag material. The photoelectric unit is adapted in a conventional way to be actuated only after a predetermined number of bag units have passed its scanning point. This can be done either with a counter or other conventional means well known in the art. Thus, the motor 86 is energized when the predetermined number of bags have passed by, and then 65 knife 83 is brought into action by the sensing of either a 70

registered dot, or the appropriate joint 18 passes the desired position. Knife 83 will therefore contact the bag material along the upper edge of the joint 18, and will stay in this relative axial position until it has transversely crossed the bag material to complete its cut. As has been stated hereinabove, this cutting action can be adjusted to take place simultaneously with the tearing action caused by the tensioning of the bag material under the influence of movable rolls 14a and 14b, or the material can be severed separately by either the tensioning action of rolls 14a and 14b, or the individual cutting action of knife 83.

After the 25th and severed bag passes through rolls 15a and 15b, solenoid 23 is again energized to complete the cycle. Arm 37 completes its revolution in the time space between the passage of the 25th bag through rollers 15a and 15b and the arrival of the first bag or unit on material 11 to start the next cycle.

It should be noted at this point that the timing sequence for all solenoids, except the above mentioned solenoid 23, is controlled by the commutator group 55. This group is rotated by arm 55a which is driven by element 39.

Before the next cycle can begin rolls 14a and 14b must be lowered to the original position. To accomplish this, the upper arms of links 51a and 51b must be permitted to drop downward. Since cams 50a and 50b would permit these arms to drop too rapidly for proper machine timing solenoid catches 54, snapped into recesses 53 in base plates 52 to delay the descent of rolls 14a and 14b until contacts 20a and 20b can energize solenoid 23. The operation of catches 54 is controlled by commutator group 55.

A cylinder feeding mechanism 56 feeds hollow tubes 16 to be wrapped to the tube wrapping mechanism 59a and 59b in proper timing by the action of tilting table 58 and three arms which are together advanced and withdrawn by the action of a cycling solenoid 57.

The tube wrapping mechanism (FIGURES 6 and 7) 59a and 59b at one end has tube support 61 secured to a shaft 60. Shaft 60 extends to an axial thrust bearing 62. When, under the control of commutator group 55, solenoid 63 is energized, splined cup 64 slides in splined housing 65 pulling support 61 against spring 66. Meanwhile shaft 60 is free to turn and is continuously driven from pulley 67 through spline 68. A tube 16 is fed into proper position within the mechanism 59a and 59b by the cylinder feeding mechanism when solenoid 63 is energized. Solenoid 63 is energized at a predetermined time by the action of commutator group 55, whereby the tube support 61 is axially withdrawn from tube 16 after the bag material has been severed either by the action of the tension rolls 14a and 14b, the cutting knife 83, or both. It should be noted that after severing has taken place between rolls 14 and 15 in the axial path of the bag material, the bag material continues its downward path towards tube 16, around which it is wrapped. The wrap and grip action, provided by member 85, as will be explained hereinbelow, insures a compact and tight wrapping of material about tube 16 at the appropriate time. Thus, it is seen that tube support 61 is withdrawn at the proper moment after severing has taken place to permit the severed end of the material to be securely wrapped around tube 16 before the wrapped roll of bag material is permitted to drop into container 17, thereby coordinating with the actuation of cylinder feeding mechanism 56, which will feed another hollow to 16 inch alignment with tube support 61, which will then be positioned to receive the new tube 16 thereon, so that the next batch of material can be wrapped. Thus, a relationship is seen between the timing of the cutting mechanism or the tearing mechanisms, and the plastic bag winding device, which is all coordinated through commutator group 55. A more detailed explanation of the commutator group 55 will follow hereinbelow.

The cutting means of FIGURES 8 and 9 as has been described hereinabove, are energized at the proper time by means of a photoelectric cell which may be activated only

after predetermined bag units have passed by its scanning point.

Accordingly, to cause the cutting means to begin its cut at the same time that the tensioning rolls 14a and 14b exert a tearing tension on the perforation, the solenoid 23 which initiates the upward axial movement of the tensioning rolls, is timed to be energized appropriately.

Housing 71 carries a radial cam 69 and an axial cam 70. A hollow shaft 72 has at one end a spring-loaded cam follower assembly 73. Shaft 72 also has a slide bearing 74. At the other end, shaft 72 has a spline 75 which carries freely therearound the "armature" section 76 of a magnetic clutch. The "field" section 77 of this clutch is energized in proper timing by commutator group 55 through slip rings 78 and contacts 79. Hollow shaft 72 which carries around armature section 76, does not rotate until the field section 77 is energized. Accordingly then, during rotation of shaft 60 when the magnetic clutch field section 77 is not energized, it is apparent that shaft 72 and armature section 76 do not rotate, and therefore, the wrap grip action of member 85, is not operative. When the magnetic clutch field section 77 is energized, hollow shaft 72 and armature section 76 are axially attracted to the field section 77, and thereby are caused to rotate along with field section 77 and the shaft 60. Inception of the rotation of hollow shaft 72, causes rotary motion of the cam follower assembly 73 and the ensuing interaction with cams 70 and 69, which results in the radio and axial wrap grip action of member 85. It is therefore seen that energization of field section 77 of the magnetic clutch at the appropriate time, brings into play the wrap grip action of member 85. The timing is controlled by the commutator group 55a to be described in greater detail hereinbelow. It is to be noted that field section 77 is mounted on shaft 60, and splined thereto by the spline 68, whereby rotary motion of the shaft 60 causes rotary motion of field section 77. In contrast, hollow shaft 72 is not splined to shaft 60, but is caused to rotate along with shaft 60 by the action of the magnetic clutch field section 77. The armature section of the magnetic clutch is splined to the hollow shaft 75, and can move axially relative to said hollow shaft 75.

When the "field" section 77 is energized, spline 75 and the spring loaded cam follower assembly 73 slide axially in the path defined by axial cam 70 and spring 66. At the same time, member 80 follows the path fixed by spring 81 and radial cam 69. The combined action indicated will provide the desired tube wrapping operation wherein material 10 is wrapped on tube 16 and wherein the wrapped tube is gripped by member 85.

To provide proper electrical connections, the "hot" voltage terminal of the voltage source required to energize all of the electrical mechanisms controlled by the commutator group is connected to each of these mechanisms directly.

The "ground" voltage terminal of the source is connected to a shaft 106 on disc 36. The commutator group 55 consists of a plurality of insulated discs 100 stacked one beside the other on a shaft 106 attached to disc 36 and rotated therewith under the control of arm 55a as explained above. Each disc carries an electrically conductive segment 104 about its periphery. Each segment is connected through wire and rings (not shown) to grounded shaft 106.

Each mechanism to be controlled by the commutator group 55 is associated with each disc 100 and has its "ground" connection connected to a brush 102 contacting the periphery of its disc 100. As the appropriate brush is moved into contact with the appropriate conductive segment 104, the appropriate mechanism is grounded and energized. Thus the arc length of each segment 104 determines the length of time of energization since disc 36 is rotated at constant speed and the electrical connections are completed only during the time the appropriate brush contacts that portion of the periphery

of the appropriate disc which contains the appropriate segment.

If desired the solenoids can be replaced by an electro-pneumatic system or any combination of both.

While I have shown and pointed out and described my invention as applied in the embodiment shown, other modifications and variations will be apparent to those skilled in the art. Therefore, it is my intention to be limited in my protection only by the terms of the claims which follow.

Having thus described my invention, I claim as new and desire to secure by Letters Patent:

1. A plastic bag machine utilizing a supply roll carrying a rolled sheet consisting of a large plurality of plastic bags in collapsed form, joined end to end, said machine comprising means to transport axially a predetermined number of said bags joined end to end to a transfer station positioned axially displaced below said roll supply; means to count said number of bags; means responsive to a predetermined number of bags counted to cause a transverse severance between the last bag in said number and the joined first bag of the next successive group; means for causing the severance to occur when a predetermined number of bags have been counted; and means for wrapping the bags on a tube which will hold a predetermined number of bags that are included between the severed portions of the rolled sheet, whereby each tube will contain a predetermined number of rolled-up bags.

2. A plastic bag machine as set forth in claim 1, wherein said transport means include a pair of stationary rolls through which said rolled sheet passes, and a pair of tearing rolls axially separated from the stationary rolls, also between which said rolled sheet passes, wherein the stationary and tearing rolls are mechanically interconnected and driven in synchronized fashion to cause an axial movement of the plastic bags towards the transfer station.

3. A plastic bag machine as set forth in claim 2, in-

cluding a separating means for displacing the tearing rolls axially relative to the stationary rolls, whereby the relative movement of the stationary and tearing rolls is coordinated by a further means to cause the said movement to occur at a predetermined time at the point where a predetermined number of bags have passed between the stationary and tearing rolls.

4. A plastic bag machine as set forth in claim 3, including means for insuring a tightly gripped wrapping of the bags about the tube when the sheet of bags are being wrapped about the tube.

5. A plastic bag machine as in claim 1, wherein the means for causing the transverse severance comprise a pair of axially fixed rolls and a pair of axially movable rolls for transporting the plastic bags to the transfer station; means for removing the axially movable rolls away from the fixed rolls at an appropriate predetermined time to cause tension in the rolled sheet sufficient to effect a transverse severance where desired.

6. A plastic bag machine as in claim 1, wherein the means for causing the transverse severance comprise a cutting knife mounted on a belt which moves transversely across the rolled sheet, having an axial component equal to the axial speed of the rolled sheet, and means for causing the knife to engage the rolled sheet at a predetermined point, causing the severance to occur after a predetermined number of bags have passed by the transfer means.
